Inventor:

G. Bonnet

UNITED STATES PATENT OFFICE.

GUSTAVE BONNET, OF NEW YORK, N. Y.

IMPROVEMENT IN HORSESHOES.

Specification forming part of Letters Patent No. 56,888, dated August 7, 1866.

To all whom it may concern:

Be it known that I, GUSTAVE BONNET, of New York city, in the county and State of New York, have invented a new and useful Improvement in Adjustable Horseshoes; and I do hereby declare that the following is a full and exact description thereof, reference being had to the accompanying drawings, and to the letters of reference marked thereon, in which—

Figure I is a perspective view of the shoe when adjusted upon the foot. Fig. II is a perspective view of the shoe detached from the foot; and Fig. III is a view of the bottom of the shoe.

The object of my invention is to construct a shoe which can be easily adjusted upon the foot and removed when the horse is brought into the stable.

To enable others skilled in the art to make and use my invention, I will proceed to describe its construction and operation.

I construct my shoe of a peculiar shape, as shown in Fig. III, the fore part, A, corresponding to the shape of the toe of the foot and extending about half-way back to the heel on each side. From the center of the toe portion extends the center portion, B, of the shoe a short distance, and is then divided into two arms, C C, which form an angle and extend back on either side of the frog to the heel. To the center of the toe of the shoe is hinged the clamp D, with the hook d at the top, (or, instead of the clamp D being hinged, it may be a spring attached firmly to the shoe,) and to the back ends of the arms C C are hinged the hooks E E, so that they may spread to accommodate themselves to the foot, and bent at the top to allow the rubber band F to pass through them.

To adjust the shoe, first put the rubber band over the foot, then place the foot in the shoe, and turn up the clamp and hooks close to the sides of the foot; then draw the rubber band down under the hook d at the toe, and through the hooks at the heel, and the shoe is fastened, ready for use.

Some of the advantages of my shoe are, first, by dispensing with nails I obviate the liability of injuring the foot, as is frequently done by driving a nail into the quick, and it also allows the foot its natural expansion in traveling, and prevents pinched feet. By the peculiar shape of my shoe I get the required protection at the toe and heel, where it is needed, with a less amount of iron than by the old-style shoe. The advantage of the rubber band is that it cannot work loose, as an inflexible band might, and a jar cannot break it or shake it off from the foot. The advantage of the shoe being easily removed from the foot need not be explained, as it is evident to any one.

Having thus described my invention, what I claim as my invention, and desire to secure by Letters Patent, is—

1. The peculiar shape of my shoe, as shown in Fig. III.
2. The rubber band F, in the combination and for the purpose specified.
3. The combination of the shoe with the clamp D, the hooks E E, and the band F, as and for the purpose specified substantially.

G. BONNET.
